CHAIR

Joseph Carl Cicchelli, Providence, R. I.

Application July 17, 1952, Serial No. 20,657

Term of patent 7 years

(Cl. D15—8)

To all whom it may concern:

Be it known that I, Joseph Carl Cicchelli, a citizen of the United States, residing at Providence, State of Rhode Island, have invented a new, original, and ornamental Design for a Chair, of which the following is a specification, reference being had to the accompanying drawing, forming a part hereof.

In the drawing,

Fig. 1 is a side elevational view of a chair showing my new design; and

Fig. 2 is a front view thereof.

I claim:

The ornamental design for a chair, as shown.

JOSEPH CARL CICCHELLI.
